 SHOE POLISHING DEVICE
 Louis J. Petion, Great Neck, N.Y.
 (11 Lake St., White Plains, N.Y.)
 Filed Jan. 15, 1964, Ser. No. 337,826
 9 Claims. (Cl. 15—534)

This invention relates to an improved shoe polishing device which combines a shoe brush, a dauber and a buffer, each mounted on a separate base plate and the three base plates removably assembled to form a triangular housing which on its inside accommodates a collapsible container of shoe polish. This triangular housing is rotatably mounted on the inside of a handle shaped cover and is provided with a knob extending to the outside of said cover as a means for rotating the housing into any of three positions and thereby exposing in a cavity which is provided in the cover, either the shoe brush, or the dauber, or the buffer.

One object of the invention is to provide a collapsible container of shoe polish which has a nozzle protruding through the cover, and a control member for conveying the polish from the container directly onto the shoe which is to be polished.

A further object of the invention is to provide a self contained unit which is designed so that either the brush, or the dauber, or the buffer, or the container of shoe polish may be disassembled and replaced in an easy manner.

The main object of the invention is to provide a hand conveniently operable unit which performs the operations of cleaning the shoe, applying the polish, distributing the polish on the shoe, brushing the polish to a shine, and then buffing it to a gloss, all with one compact unit.

These together with various auxiliary features and objects of the invention which will later become apparent as the following description proceeds are attained by this device, a preferred embodiment of which has been illustrated by way of example only, in the accompanying drawings, whereas:

FIGURE 1 is a perspective view of the shoe polishing device with the nozzle cap removed;

FIGURE 2 is a longitudinal vertical sectional view;

FIGURE 3 is a horizontal longitudinal sectional view of FIGURE 1 with the cover removed, showing in top plane the upper section of the shoe brush, and a cut away portion which shows the polish dispensing mechanism;

FIGURE 4 is a vertical transverse sectional view through the cover of FIGURE 1, showing the interior arrangement;

FIGURE 5 is an end view particularly illustrating the device with the dauber exposed for use;

FIGURE 6 is a front view particularly illustrating the device with the brush exposed for use.

Referring to the drawings, the shoe polishing device of the present invention comprises a platform 10 with tufts of bristles 12 embedded on one plane, to form a polishing brush 14 and the opposite plane of said platform accommodates a collapsible container 16 filled with a cream shoe polish. The front end of said platform 10 is provided with a perpendicular triangular bracket 20 which has on its interior face two grooves 22. The rear end of said platform 10 is also provided with a perpendicular triangular bracket 26 which has two grooves 28 opposed to the grooves 22 in the front bracket 20.

A dauber 32 is mounted on a base plate 34, said base plate is slidably installed in the grooves 22 and 28 of the brackets 20 and 26, said base plate 34 is provided with a slot 36 which serves as a locking means. A buffer 38 made of a polishing material such as foam rubber, lamb's wool or any other suitable material, is

2

mounted on a base plate 40, said base plate is slideably installed in the grooves 22 and 28 of the brackets 20 and 26, said base plate 40 has a lug 42 which engages the slot 36 in the base plate 34 and which serves as a locking means when both base plates 34 and 40 are installed, said lug 42 snaps into the slot 36 when the base plate 34 is being installed. In order to disengage said lug 42, the center portion of the base plate 34 may be pulled away from said lug 42.

10 A cover 44 is provided with openings at opposite ends, said openings being generally parallel to the polish container 16 and in alignment with each other; the forward opening journals on the protruding bearing 46 of the bracket 20 and the rear opening of said cover 44 journals on the undercut 50 of the knob 48, said knob serves as a convenient means for rotating the platform 10 inside of the cover 44.

15 A pin 52 extends outwardly from the bracket 26. Three holes 54 are provided in the rear of the cover 44, said holes are located on the same radius from the axis of rotation as said pin 52 and said holes 54 are spaced so as to engage said pin 52 when either the brush 14 or the dauber 32 or the buffer 38 is exposed in the cavity of the cover 44. A spring 56 is located between the cover 44 and the bracket 20 for the purpose of keeping the pin 52 engaged in one of the holes 54 when the shoe polisher is in operation.

20 A neck 60 is provided with an external thread 62, said neck extends from the collapsible container 16 and protrudes through an opening in the bracket 20 to the exterior of the cover 44. A nozzle 66, for conveying the polish, is provided with an internal thread to engage the thread 62 of the neck 60, and a flange 70. A cap 64 prevents the polish from drying up when the device is not in use.

25 A squeezer 72 is provided with a threaded hole 73, said hole engages a threaded shaft 74. The bottom of said squeezer 72 is spaced from the top of the platform 10 to accommodate the collapsed end of the container 16. The threaded shaft 74 is parallel with the top of the platform 10 and has its ends rotatably mounted in the brackets 20 and 26. One end of said shaft 74 extends through the knob 48 and has a knob 80 secured to the protruding end, said knob 80, when pressed in and rotated, will set the squeezer 72 in a forward motion and force the polish through the nozzle 66 onto the shoe. A spring 81 is located on said threaded shaft 74 between the knob 48 and the knob 80 for the purpose of receding the squeezer 72 after the polish has been dispensed and the knob 80 has been released; the receding of said knob 80 relieves the pressure on the container 16 and eliminates further oozing out of polish through the nozzle 66. The front part 82 of the squeezer 72 has a convex shape which enters the hard tapered flange 84 of the container 16 and thereby expels the maximum amount of polish from said container 16.

30 When the manipulator wishes to employ the polishing device, he holds the handle shaped cover 44 with the brush 14 exposed, in his hand and brushes the dust or dirt from the shoe; then he directs the nozzle 66 towards the tip of the shoe, presses the knob 80 in and rotates it until a sufficient amount of shoe polish has been dispensed; then he presses the knob 48 in and rotates it until the dauber 32 is exposed and the pin 52 has engaged the hole 54; then he utilizes the dauber to distribute the polish all over the shoe; then again he presses the knob 48 in and rotates it until the brush 14 is exposed, which he utilizes for shining the shoe; next he presses the knob 48 in and rotates it until the buffer 38 is exposed, which he utilizes to put a final gloss to the shoe.

35 When the polish in the container 16 becomes exhausted, a new container may be substituted easily by rotating the

knob 48 into the intermediary position so that the locking device of the base plate 40 and the base plate 34 is exposed in the cavity of the cover 44. The lug 42 of the base plate 40 may now be disengaged from the slot 36 and said base plate 34 may now be removed from the brackets 20 and 24. Now the knob 80 is rotated until the squeezer 72 reaches its starting position at the collapsed end of the container 16. Then the nozzle 66 is removed from the neck 60 and the container is now disconnected for removal. A fresh container may now be installed on the platform 10 and secured in place with the nozzle 66. After the base plate 34 has been reinstalled, the shoe polisher is again ready for use.

From the foregoing, the manner of constructing and operating the device, together with the numerous advantages, will be readily understood and further explanation is believed to be unnecessary. However, since numerous changes will readily occur to those skilled in the art after consideration of the foregoing specifications and accompanying drawings, it is not desired to limit the invention to the exact construction shown and described, but all suitable modifications and equivalents may be resorted to falling within the scope of the appended claims.

Having thus disclosed and described the invention, what is claimed as new is:

1. In a shoe polishing device, the combination comprising an elongated platform with opposed triangular end brackets, said platform having means for holding on its bottom side a shoe brush and on its top side a collapsible container of shoe polish, said container having its discharge end projecting through an opening in one of said end brackets, means for ejecting polish from said container, a dauber mounted on an elongated base plate, said base plate having its ends removably secured to said end brackets, a buffing material mounted on an elongated base plate, said base plate having its ends removably secured to said end brackets opposite said dauber base plate, a cover defining a cavity for selectively accommodating at once any two of the brush, dauber and buffer, said cover having an open side so as to expose the third work contacting element which is not enclosed, means for establishing an axis of rotation of said platform with respect to said cover, and means for mounting said platform for rotation about said axis between the end walls of said cover.

2. In a shoe polishing device, the combination comprising an elongated platform with opposed triangular end brackets, said platform having means for holding on its bottom side a shoe brush and on its top side a collapsible container of shoe polish, said container having its discharge end projecting through an aperture in one of said end brackets, means for ejecting polish from said container, a dauber brush mounted on an elongated base plate, said base plate having its ends removably secured to said end brackets, a buffer mounted on an elongated base plate, said base plate having its ends removably secured to said end brackets opposite the dauber base plate, bearings on the exterior of said end brackets, a cover having apertures which journal on said bearings, a knob for rotating said platform, and a cavity in said cover for selectively enclosing at once any two of the brush, dauber and buffer, said cover having an open side so as to expose the third work contacting element which is not enclosed.

3. In a shoe polishing device, the combination comprising an elongated platform with opposed triangular end brackets, said platform having means for holding on its bottom side a shoe brush and on its top side a collapsible container of shoe polish, said container having its discharge end projecting through an aperture in one of said end brackets, means for ejecting polish from said container, a dauber mounted on an elongated base plate, a buffer mounted on an elongated base plate, grooves on the inside of said end brackets for removably receiving the dauber base plate and the buffer base plate to form jointly with the platform a triangular housing, a cover defining a

cavity for simultaneously receiving any two of the three work contacting elements and said cover being open along one side thereof for selectively exposing either the brush, or the dauber, or the buffer, means for establishing an axis of rotation of said platform with respect to the end walls of said cover, and means for mounting said platform for rotation between said end walls.

4. The device of claim 3 wherein the dauber base plate is provided with a slot, and the buffer base plate is provided with a lug, and whereby said slot and said lug interlock when said dauber base plate and said buffer base plate are installed in the grooves of the end brackets.

5. The device of claim 3, wherein the rear end bracket is provided with a pin and the adjacent end wall of the cover is provided with three holes for receiving said pin, said pin and said holes being located on the circumference of a circle about said axis of rotation, said holes being spaced so that when they engage the pin either the brush or the dauber or the buffer is exposed at the open side of the cover, and a spring located between the front bracket and the front end wall of the cover, said spring keeping the pin from disengaging the hole when the polishing device is in operation.

6. A shoe polishing device comprising a handle forming a hollow cover with opposed end walls, an elongated platform having two faces and two end brackets, a polishing brush located on one face of said platform, a collapsible polish containing tube mounted on the other face of said platform, said tube having its discharge end protruding through an aperture in one of said end brackets, a squeezer provided with a threaded hole engaged on a threaded shaft, said threaded shaft parallel with the platform and its ends rotatably mounted in the end brackets, a control member and means responsive to the manipulation of said control member for setting said squeezer into motion and thereby compressing said collapsible tube and ejecting the polish from said tube, a dauber mounted on a separate plate, a buffer mounted on a separate plate, means for removably securing said dauber and buffer base plates to said end brackets, and a knob protruding to the outside of said cover for rotating said platform inside of said cover so as to selectively house any two of said buffer, brush or dauber and expose for use the third work contacting means which is not being housed.

7. The device of claim 6 wherein the squeezer is spaced from the platform to allow receiving the collapsed end of said tube, and said squeezer has a convex shaped front which will enter the hard tapered end of the collapsible tube when said tube is almost empty.

8. The device of claim 6 wherein the threaded shaft protrudes through the knob which rotates the platform, another knob is secured to the protruding end of said threaded shaft, and a spring is positioned between said knobs, said spring forces the squeezer to recede after the polish has been dispensed and thereby relieves the pressure on the tube and eliminates oozing out of the polish.

9. A shoe polishing device comprising an elongated platform with perpendicular triangular brackets at each end, bearings on the outside of said end brackets, a shoe brush mounted on one side of said platform, a collapsible container of shoe polish mounted on the other side of said platform, a dauber mounted on an elongated base plate, a buffer mounted on another elongated base plate, said dauber and buffer base plates being removably disposed in grooves provided on the inside of said end brackets and forming a triangular housing in conjunction with said platform, a neck with an external thread extending from said polish container, an aperture in one of said end brackets, said aperture accommodates the neck of said container, a nozzle for conveying the polish, said nozzle being provided with an internal thread for engaging the external thread of said neck and thereby securing said container to said end bracket, a squeezer moving on a threaded shaft, means for rotating said shaft and setting the squeezer into a forward motion and thereby flattening

the tube and expelling the polish through said nozzle, a handle shaped cover having two end walls and a cavity opening on one side, openings in said end walls, said openings being on the same axis with the bearings of said end brackets, and means for rotating said platform inside of said cover so as to selectively house any two of the shoe brush, the dauber or the buffer and exposing the third work contacting element.
